UNITED STATES PATENT OFFICE

2,439,695

COMBUSTION GAS TURBINE

Charles F. Rocheville, West Los Angeles, Calif.

Application March 21, 1944, Serial No. 527,393

5 Claims. (Cl. 60—41)

1

This invention relates to an internal combustion engine and particularly refers to an arrangement of blades or vanes for a rotary type of prime mover in which a combustible mixture is ignited in a rotating combustion chamber and expands therefrom to impinge against a plurality of blades or vanes, the reaction of which drives forwardly the combustion chamber and its supporting shaft to generate power. The apparatus disclosed and claimed herein is an improvement over that of my Patent No. 2,222,183, issued November 19, 1940.

The expansion means of the apparatus of my previous patent were illustrated as being inclined slots or recesses which lined the greater part of the stator within which moved the rotor carrying the combustion chamber, the latter being provided with a trailing member which was correspondingly slotted to cooperate with the stator to provide a tortuous passage for the escape of the heated gas from the outlet of the combustion chamber.

This invention comprehends broadly an improved arrangement of blades or vanes which are similarly located in the stator and following the combustion chamber of the rotor of a turbine of the type of my previous patent. Reference is hereby made to that patent for the general features of construction, and this disclosure will be primarily concerned with the specific arrangement of the combustion chamber with its vanes or blades and the blading arrangement for the stator, the latter being shaped as a toroid to form an annular chamber through which the combustion chamber and its blades are adapted to rotate.

It is an object of this invention to provide a combustion gas turbine blading arrangement which will give a higher efficiency than that heretofore attained, using airfoil blade sections and a plurality of stages through which the expanding gases may pass to give a reaction which will drive the rotor to produce power.

Another object is to provide an improved blading arrangement for the rotor and stator of a turbine of this type in which the several rows of vanes are radially mounted within a toroidal chamber, the flow of gas being divided to balance the end thrust.

Another object is to provide an improved vane arrangement for a combustion turbine of this type in which the vanes may be separately fabricated and installed by sliding them lengthwise into grooves which extend circumferentially around at least a portion of the stator and rotor.

These and other objects and advantages will become further apparent from the following description and from the accompanying drawing

2

which forms a part of this specification and illustrates a preferred embodiment of the invention.

In the drawing,

Figure 1 is a vertical sectional view at right angles to the shaft of the combustion turbine and in the plane of rotation of the rotor.

Figure 2 is a part sectional vertical view on line II—II of Figure 1 and illustrates an end view of the vanes and part of the combustion chamber arrangement to an enlarged scale.

Referring to the drawing, reference numeral 10 designates generally a circular casing which for convenience may be split circumferentially into two parts and joined by cooperating flanges 11 secured by screws 12. Desirably, but not necessarily, the outer part of casing 10 is provided with an outer jacket 13 to form a space 14 through which water or other cooling fluid may be circulated. The inner wall 15 of casing 10 forming the toroidal chamber is desirably recessed with longitudinally extending grooves 16 to receive the stator gas reversing blades 17 and stator gas splitting blades 18, the latter bridging the plane of separation between the two halves of casing 10 and are those against which the gases from the combustion chamber are first directed.

Blades 17 and 18 extend circumferentially in spaced rows around that part of the periphery of the annular or toroidal chamber 19 formed by inner wall 15 in a clockwise direction between points 20 and 21 (Figure 1), which constitutes the effective sector angle through which the reaction of gases from the rotor tends to drive the latter. That portion or sector of the annular chamber 19

which extends in a clockwise direction between point 21 and point 20, constituting the remainder of the 360 degrees of chamber 19, is provided with a solid blank sealing member 22 which has the same outer configuration as the stator gas splitting blade 18, and serves to seal off the outlet from the combustion chamber, to be described below, during the intake and compression periods while said combustion chamber is receiving its combustible mixture from an inner port as described in my Patent No. 2,222,183. Stator gas reversing blades 17 similarly extend clockwise from points 20 and 21 but there is no filler or sealing member continuing the circle between the two latter points, this space serving to receive the exhaust

gases which have already passed through the expansion vanes and conducts such bases to ports 23 through wall 15 and to exhaust pipe 24.

Rotor 25, in this example, consists of a ring 26 which is suitably mounted for rotation in casing 10 by means not shown but which could be

arranged as in my Patent No. 2,222,183, said ring carrying at one point on its periphery a hollow combustion chamber 27 provided with an intake port 28 to receive a combustible charge throughout a predetermined part of its travel through annular chamber 19 from suitable charge regulating means inside of ring 26. The ignition of the combustible charge within chamber 27 may be carried out either through the heat of compression of the combustible charge, as in a Diesel operation, or may be carried out by means of a spark plug or other suitable igniter which is adapted to be placed in communication with port 28 at the proper point in the revolution of chamber 27 throughout its path. Chamber 27 is provided with one or more discharge ports 29 on the outer face or periphery of chamber 27, preferably in the plane of separation between the two halves of casing 18. Thus the gases emerging from ports 29 will, during that period of the rotation of the rotor 25 when these ports are in the sector which extends clockwise between points 20 and 21, impinge against the working faces of the stator gas splitting blades 18, and there will be divided to flow as indicated by the arrows of Figure 2 to pass transversely around the annular passage between the body of the combustion chamber 27 and its trailing portion 30 to impinge against the blades occupying that passage. As shown in Figures 1 and 2, each of blades 18 has a raised ridge or fin 31 on its forward face, said fin sloping gradually away from the center to form what may be termed a dihedral face on blade 18, so that the gases passing backwardly from ports 29 will be divided and directed into the paths just mentioned.

The trailing member 30 carried by combustion chamber 27 is provided, in the example shown, with four rows of blades or vanes which may conveniently be described in two groups, Nos. 32 being the first stage and Nos. 33 constituting the second stage. These vanes are received in grooves 34 and 35 respectively which are suitably recessed into the trailing member 30. Desirably blades 32 are provided with a thick leading edge 36 and a thin trailing edge 37, the intermediate portion of the blade being of any desired concavo-convex configuration similar to those used for high efficiency airfoil sections.

Referring now to the first stage blades 32, the gases leaving the sides of splitter blades 18 will impinge against the thick leading edges 36 of blades 32 in the same manner as air impinges against the leading edge of an airfoil section in an airplane, the concavity and convexity of blades 32 being arranged to urge those vanes and the rotor 25 supporting them in counterclockwise direction within passage 19. The gases leaving the thin trailing edges 37 of first stage rotating vanes 32 will impinge upon the thick leading edges 38 of the stator stationary reversing blades 17 to straighten the flow of gas. Reversing blades 17 are similarly of airfoil section but with the concavity and convexity reversed in direction from blades 32 so that this straightening action will cause the gases, when they leave the thin or trailing edges 39 of blades 17 to impinge upon the thick leading edges 40 of the second stage rotor vanes 33. These latter have their concavo-convex surfaces in the same relative position as blades 32, although at a different angle, if desired, the gases leaving their trailing edges 41 passing freely into the annular chamber 19 and eventually making their way through ports 23 to exhaust pipe 24. Blades 32 and 33 are secured with

in grooves 34 and 35, respectively, by an end plate 42 which is fastened to the trailing end portion of member 30 on rotor 25. Such an arrangement will be found to facilitate the assembly and maintenance of these blades, which should desirably be constructed of a chromium-molybdenum alloy which will resist temperatures upwardly of 1200 to 1800° F. Similarly blades 17 and 33 of the stator and combustion chamber 27 should be made from an alloy having adequate heat resisting qualities.

In operation, combustion chamber 27 will receive a combustible charge through port 28 during that portion of the time that discharge ports 29 are sealed by the blank member 22 which extends clockwise between points 21 and 20. After this intake period is completed the charge in 27 is ignited, for example as by the means shown in my Patent No. 2,222,183 and, as soon as the burning gases have begun to expand, they are ejected through discharge ports 29 against those stationary splitter vanes 18 which are immediately adjacent point 21, after which the gases pass transversely in two directions around the toroidal passage formed between member 30 at the trailing end of the combustion chamber 27 and the wall 15 of the housing 10, these expanding gases being directed first against movable blades 32, then reversed in direction by stationary blades 17 and finally directed against second stage blades 33. The reaction of these gases emerging from ports 29 and impinging against blades 32 and 33 will serve to urge the rotor 25 to travel in a counterclockwise direction within housing 10 to rotate its support shaft and generate power.

It will be appreciated that this invention is directed primarily to an improved vane arrangement and construction for a rotating combustion gas turbine of the type of my previous Patent No. 2,222,183 and includes generally a plurality of radially outwardly extending vanes carried by a rotating combustion chamber adjacent the outlet of the latter, and a plurality of radially inwardly extending vanes in the toroidal combustion chamber housing, all of the vanes cooperating to form a tortuous passage for combustion gases discharged from the combustion chamber into the rotor housing to produce rotation of the combustion chamber within said housing. Although only one specific construction and mode of operation is here shown and described, it is understood that many changes and modifications could be made without departing from the essential features of the invention and all such modifications as come within the scope of the appended claims are embraced thereby.

I claim:

1. In a gas combustion turbine which includes a housing forming a toroidal passage and a combustion chamber rotatable throughout said passage and provided with a gas outlet port on its periphery, the combination of a trailing member for said combustion chamber, a plurality of rows of vanes extending around said member, said toroidal passage having a plurality of rows of vanes coacting with said vanes on said trailing member to form a tortuous passage for combustion gases from said outlet port into said toroidal passage to produce rotation of said combustion chamber.

2. A gas combustion turbine according to claim 1 in which those inwardly projecting vanes in said housing which are opposed to the outlet passage from said combustion chamber are provided with dihedral faces to divide and direct the

combustion gases in opposite directions transversely around the toroidal passage.

3. In a gas combustion turbine which includes a housing forming a toroidal passage and a combustion chamber concentrically mounted in said passage to be rotatable therethrough and provided with a gas outlet on its outer face, means comprising a plurality of spaced stationary vanes in said housing, a trailing member for said combustion chamber, a plurality of spaced movable said gas outlet, said stationary vanes extending inwardly through the spaces between said movable vanes, and said movable vanes extending outwardly through the spaces between said stationary vanes, all of said vanes cooperating to form a tortuous passage for combustion gases from said outlet port into said toroidal passage to produce rotation of said combustion chamber.

4. A gas combustion turbine according to claim 3 in which said trailing member is circular in cross-section and cooperates with said vanes to

direct the flow of gas around said trailing element and through the space defined by the inner surface of said toroidal passage and said trailing element.

5. A gas combustion turbine according to claim 3 in which the stationary vanes opposite the path of said gas outlet are provided with dihedral faces to direct the combustion gases in opposite directions transversely around the toroidal passage in the space defined by the inner surface of said passage and said trailing element.
